UNITED STATES PATENT OFFICE

GEORGE W. HARLEY, OF COLLINGSWOOD, NEW JERSEY

PATTERN AND GUIDE STRIP

Application filed October 31, 1927. Serial No. 230,116.

The present invention relates to pattern and guide strips such as are used in laying plastic floorings and has for an object to augment the strips with anchor and gauge elements to retain the strips from all displacement.

Another object of the invention is to equip the guide strips with anchoring and gauge elements which are so formed that distortion 10 along the parallel edges of the strip, during manufacture, is prevented.

A further object of the invention is to form anchor and guide elements on the strip in such a manner that lateral tilting of the strip, 15 either when the latter is imbedded in the screed coat or when the mosaic coat is poured, is effectively prevented.

Other objects of the invention will be apparent from the following description of the 20 present preferred forms of the invention, taken in connection with the accompanying drawings, wherein:

Figure 1 is a fragmentary side elevational view of a strip constructed in accordance with 25 the present invention, showing the anchor and guide plate turned outwardly into operative position;

Figure 2 is a longitudinal sectional view of 30 the same; and,

Figure 3 is a fragmentary side elevational view of a strip constructed in accordance with the present invention, showing the anchor plate in an inoperative position.

In the drawings, a strip 4 is illustrated 35 which, except for the anchor plate hereinafter described, is of standard construction. The strip has horizontally arranged incisions 5 cut therein, which are parallel to the longitudinal edges of the strip. Vertical incisions 6 extend 40 from the terminals of the incisions 5, each of which is intersected, midway its ends, by a pair of incisions 7. By cutting the strip in this manner, a plate 8 is stamped in the strip, portions of the ends of which issue into ribbons 45 or straps 9. The outer ends of the ribbons merge into the body of the strip.

In use, the plate 8 is turned a quarter of a revolution, so as to project the lateral edges thereof beyond the sides of the strip. This 50 provides an anchoring and gauge portion on

directly opposite sides of the strip. Correspondingly, an opening is provided above each plate designated A, while an opening is provided beneath each plate designated B. When the strip is pressed into the screed coat, 55 in a manner well-known in the art, the portions of each plate, which project beyond the strip, will impinge against the surface of the screed coat. The plastic material, constituting the screed coat passes through the lower 60 opening B of the strip. The mosaic or upper layer of plastic material is poured on top of the projecting portions of the anchor plate and permitted to flow through the upper opening A. Consequently, when the plastic 65 material hardens, the screed and mosaic coats are bonded together into a substantially monolithic structure.

It is manifest that the anchor plates may be twisted into an operative position on the 70 job, thereby permitting the strips to be shipped flat. When the plates are twisted into an operative position, the upper and lower faces thereof are parallel to the edges of the strips. Not only do the plates anchor 75 the strips, but by reason of their protruding portions at directly opposite points on the strip, lateral tilting of the plate is prevented. Additionally, the plate may be stamped out at any portion of the strip desired intermediate 80 the edges to regulate the depth of the mosaic or finishing coat. This form of strip provides an exceedingly simple and effective structure without in any way militating 85 against the normal use of the strip and providing a structure which may be manufactured at a very low cost.

What is claimed is:

1. A guide and pattern strip including a strip body having straight edges and equipped with portions struck out from the body and projecting in a horizontal plane at directly opposite points on the strip intermediate said straight edges. 90

2. An anchor and gauge for guide and pattern strips including a strip having straight edges and equipped with a plate extending through the strip intermediate said edges, the faces of which are parallel to the longitudinal axis of the strip, the lateral margins of said 95 100

plate projecting beyond the sides of the strip.

3. An anchor and gauge for guide and pattern strips including a strip equipped with a plate, twisted in the body of the strip with portions projecting on opposite sides of the strip, the faces of the plate being parallel to the longitudinal edges of the strip.
  4. A guide and pattern strip including a strip having straight edges, a plate formed on said strip intermediate the edges thereof, said strip having openings above and below the plate.
  5. A method of making a pattern and guide strip consisting in incising the strip intermediate its marginal edges to define a plate, after which the plate is twisted to project portions thereof on both sides of the strip, the faces of which are parallel to the longitudinal axis of the strip.
  6. A pattern strip including a strip body, a portion of said body being bent out to project on both sides of the strip, the faces of said bent out portion being parallel to the longitudinal axis of the strip.
